S. O'HARA

MACHINE FOR PRINTING OR EMBOSsing

Filed May 20, 1927

Fig. 2.

Fig. 1.

This technical drawing illustrates a mechanical assembly, likely a lock or a similar device. The drawing is labeled with various numbers:

- 36: Located at the top left and bottom left.
- 35: Located in the upper left area.
- 32: Located in the upper left area.
- 37: Located in the center left area.
- 24: Located below 37.
- 34: Located below 24.
- 36: Located below 34.
- 26: Located below 36.
- 26: Located below 26.
- 25: Located at the bottom center.
- 11: Located at the top center.
- 17: Located at the top right.
- 20: Located at the top right.
- 16: Located in the upper right area.
- 14: Located in the upper right area.
- 18: Located in the upper right area.
- 11: Located in the middle right area.
- 10: Located in the middle right area.
- 28: Located on the right side.
- 29: Located on the right side.
- 30: Located on the right side.
- 27: Located at the bottom right.

The drawing also includes a circular component with markings and a wavy line on the left side.

SKIDMORE O'HARA, OF WALTHAM, MASSACHUSETTS, ASSIGNOR TO O'HARA WALTHAM COMPANY, OF WALTHAM, MASSACHUSETTS, A CORPORATION OF MASSACHUSETTS.

MACHINE FOR PRINTING OR EMBOSsing.

Application filed May 20, 1927. Serial No. 193,040.

The invention relates to an improvement in machines for printing or embossing. It is especially applicable to machines for printing or embossing on glass, china, porcelain, 5 enamelled goods or other frangible articles, but it is not limited to machines for printing on articles of that character. It relates especially to machines in which the printing or embossing member is reciprocable and has 10 a printing surface on which a marking or design is imprinted or embossed by a die in such manner that the printing surface is adapted to imprint or emboss the said design on the work, the die and work holder being 15 alternately brought into alignment with the printing member, the printing member being pressed into engagement with the die which is then moved out of position, the work holder containing the work being then 20 moved into position where the printing member imprints or embosses the design on the work.

The present invention relates especially to the means for actuating the work holder. 25 The invention will be understood from the following description when taken in connection with the accompanying drawings, and the novel features thereof will be pointed out and clearly defined in the claims 30 at the close of this specification.

In the drawings:

Fig. 1 is a side elevation of a fragmentary portion of a machine embodying the invention showing the printing member in its 35 raised position and the die in a position intermediate its most retracted and its most forward position before it reaches its position under the printing member, the work holder being in a partially retracted position out from under the printing member.

Fig. 2 is an end elevation viewed from the left-hand side of Fig. 1.

Fig. 3 is a section on line 3—3 of Fig. 1.

Fig. 4 is a fragmentary view on the same 45 line as Fig. 3 showing the work holder positioned beneath the printing member.

Referring to the drawings, there is shown at 10 a frame or casting to hold the parts, said frame having overhanging arms 11 supporting a bearing 12 in which a plunger 13 is vertically reciprocated. Said plunger carries on its lower end a member 9 to which is secured a pad 15 of gelatin or other suitable material having a surface adapted to

take ink or other printing substance from a die and which is adapted to imprint the design on the work when the printing pad is brought into engagement with the work. The said plunger may be operated by any suitable means for raising and lowering it. 55 Mounted in guide ways 16 in the frame is a slide 17 on which is mounted a die 14 on which is formed the design to be imprinted or embossed on the work. Said die carrier 17 is slidable in said guide ways to bring the die into and out of alignment with the printing member 15. Secured to the under-side of said die carrier 17 is a rack 18 which engages with a gear 19 mounted on a shaft 20 journalled in bearings in the frame of the 60 machine. Said shaft 20 is adapted to be rotated on its axis alternately in opposite directions to move the said die carrier and die from its most rearward position to its forward position under the printing member, 65 then to move the die and die carrier back to its rearward position again. An inking roll 21 is engaged by the die during its movement. A wiper 22 is provided to remove the surplus ink from the die. 70

A work holder 24 is mounted upon a slide 25 which slides in grooved ways 26 in a bracket 27 and is adapted to be reciprocated in said ways so as to move the work holder into a position directly beneath the printing member and then out from under the printing member. As shown in the drawings the path of movement of the work holder is in a direction at right angles to the path of movement of the die and the die carrier. 75 It is not necessary, however, that they should have exactly this angular relation, the essential feature being that the work holder and the die may be alternately positioned beneath the printing member. 80

A lever 28 is pivoted at 29 on a vertical axis in a bracket 30 projecting from the frame of the machine and extends in a horizontal plane slightly below the plane of the die carrier 17 and the work carrier 25. Said lever 28 has at its moving end arms 31 and 32 which are respectively adapted to engage with a downwardly extending projection 33 on the under-side of the die carrier 17 and with a downwardly extending projection 34 on the 85 under-side of the work carrier 25. 100

When the die carrier is moved forward to position the die 14 beneath the printing mem-

ber the said forward movement of the die carrier will cause the said projection 33 on the under-side of the carrier to press against the end of the arm 31 and thereby swing the lever 28 on its fulcrum in counterclockwise direction as viewed in Fig. 3 and thus cause the end of the arm 32 which engages with the projection 34 on the under-side of the work carrier to move the work carrier 25 in a rearward direction, that is, away from the printing member. Said arms 31 and 32 are curved on the arc of a circle at the center of which is the pivot 29 so located with relation to the path of movement of the die carrier and the work carrier that the said two arms 31 and 32 will actuate the said carriers to move in straight paths at right angles to each other.

A spring 35 is provided, one end of which is connected at 36 with the frame of the machine and the other end of which is connected with a member 37 projecting from the work carrier 25. When the work carrier is moved backward from beneath the printing member the said spring 35 will be expanded as shown in Figs. 2 and 3 and when the die carrier moves back from under the printing member so that the lever 28 is free to respond to the action of the spring, the spring will contract and cause the lever to swing in a clockwise direction from the position shown in Fig. 3 the spring 35 will move the work holder forward to a position beneath the printing member. The die carrier will be retracted by the reverse rotation of the shaft 20. The means shown in the drawing for adjusting the range of movement of the plunger 13 consists of a hand wheel 38 and suitable mechanism engaging with the worm shaft 39 but the mechanism is not shown in detail as this does not form a part of the invention and any other suitable means may be employed.

The means for operating the plunger to make its up and down stroke in printing is not shown as that forms no part of the present invention.

What I claim is:

1. A machine of the character described having a vertically reciprocable printing member, a die mounted on a carrier adapted to move the die into and out of alignment with the printing member, a work holder mounted on a carrier adapted to move the work holder into and out of alignment with the printing member, means for reciprocating the die carrier, a lever fulcrumed intermediate its ends and having arms which respectively engage with the die carrier and the work carrier whereby when the die carrier is moved in a direction to position the die beneath the printing member the said lever will be turned on its fulcrum in a direction to move the work carrier away from the printing member and means for

moving the work carrier to position the work beneath the printing member when the die carrier is retracted.

2. A machine of the character described having a vertically reciprocable printing member, a die mounted on a carrier adapted to move the die into and out of alignment with the printing member, a workholder mounted on a carrier adapted to move the workholder into and out of alignment with the printing member, means for reciprocating the die carrier, a pivoted lever fulcrumed intermediate its ends and having arms which respectively engage with the die carrier and the work carrier whereby when the die carrier is moved in a direction to position the die beneath the printing member the said lever will be turned on its fulcrum in a direction to move the work carrier away from the printing member and means for moving the work carrier to position the work beneath the printing member and to turn the lever backward on its fulcrum to follow up the die carrier when the die carrier is retracted.

3. A machine of the character described having a vertically reciprocable printing member, a die mounted on a carrier adapted to move the die into and out of alignment with the printing member, a work holder mounted on a carrier adapted to move the work holder into and out of alignment with the printing member, means for reciprocating the die carrier, a pivoted lever fulcrumed intermediate its ends having arms which respectively engage with the die carrier and the work carrier whereby when the die carrier is moved in a direction to position the die beneath the printing member the said lever will be turned on its fulcrum in a direction to move the work carrier away from the printing member and a spring having one end secured to a fixed support and the other end connected with the work carrier so constructed and arranged that when the work carrier is moved away from the printing member the said spring will store up energy and when the die carrier is drawn from its position beneath the printing member the said spring will move the work carrier forward into a position beneath the printing member and will turn said lever on its fulcrum into operative position for the next forward movement of the die carrier.

4. A machine of the character described having a vertically reciprocable printing member, a die mounted on a reciprocable carrier adapted to move the die into and out of alignment with the printing member, a work holder mounted on a reciprocable carrier adapted to move the work holder into and out of alignment with the printing member, rack and gear mechanism adapted to reciprocate said die carrier, a pivoted lever

115

120

125

130

having arms which respectively engage the die carrier and the work carrier whereby when the die carrier is moved in a direction to position the die in operative position with relation to the printing member the said lever will be turned on its fulcrum in a direction to move the work carrier away from the printing member, means for actuating the work carrier to move the work holder

into operative position with relation to the printing member said actuating mechanism for positioning the work carrier being held inoperative while the die is beneath the printing member and becoming operative when the die carrier moves out of alinement with the printing member.

In testimony whereof I affix my signature.
SKIDMORE O'HARA.
